[57] CLAIM

The ornamental design for a fishing lure, substantially as shown.

DESCRIPTION

FIG. 1 is a top perspective view of a fishing lure in quiescent condition showing my new design;

FIG. 2 is a top plan view thereof;
FIG. 3 is a left side elevational view thereof;
FIG. 4 is a right side elevational view thereof;
FIG. 5 is a bottom plan view thereof;
FIG. 6 is a front elevational view thereof;
FIG. 7 is a rear elevational view thereof;
FIG. 8 is a top perspective view thereof in dynamic condition;
FIG. 9 is a top plan view thereof in dynamic condition;
FIG. 10 is a left side elevational view thereof in dynamic condition;
FIG. 11 is a right side elevational view thereof in dynamic condition;
FIG. 12 is a bottom plan view thereof in dynamic condition;
FIG. 13 is a front elevational view thereof in dynamic condition;
FIG. 14 is a rear elevational view thereof in dynamic condition;
FIG. 15 is a top perspective view of the head portion thereof;
FIG. 16 is a top plan view of the head portion thereof;
FIG. 17 is a left side elevational view of the head portion thereof;
FIG. 18 is a right side elevational view of the head portion thereof;
FIG. 19 is a bottom plan view of the head portion thereof;
FIG. 20 is a front elevational view of the head portion thereof; and
FIG. 21 is a rear elevational view of the head portion thereof.
